UNITED STATES PATENT OFFICE.

REUBEN SUMNER TRASK, OF ALPENA, MICHIGAN.

DEVICE FOR MOVING LOADED WAGONS.

SPECIFICATION forming part of Letters Patent No. 631,480, dated August 22, 1899.

Application filed March 21, 1899. Serial No. 710,007. (No model.)

To all whom it may concern:

Be it known that I, REUBEN SUMNER TRASK, a citizen of the United States, residing at Alpena, in the county of Alpena and State of Michigan, have invented certain new and useful improvements in devices for moving loaded wagons, trucks, carts, and mounted artillery up hills and out of mud-holes and bad roads; and I do hereby declare the following to be a full, clear, and exact description of the invention, such as will enable others skilled in the art to which it appertains to make and use same.

My invention is an improvement in devices for moving heavy loads on wagons, trucks, carts, and mounted artillery out of mud-holes, ruts, and bad roads and up hills; and it consists in the novel features of construction hereinafter fully described.

In the accompanying drawings I have illustrated one form in which I have contemplated embodying my invention, and the same is fully disclosed in the following description and claims.

Figure 1 is a plan view showing the front truck of a wagon or the like with my improvement applied thereto. Fig. 2 is an elevation of the parts shown in Fig. 1. Fig. 3 is a detail of the ratchet and pawl. Fig. 4 is a detail of a portion of one wheel and the sprocket-gear attached thereto. Fig. 5 is a detail of the brace and bearing E. Fig. 6 is a detail view of the bearing F, and Fig. 7 is a detail of the tongue-support.

Similar letters refer to similar parts throughout the several views.

My improved moving device consists of a horse-power attachment for wagons, trucks, carts, and mounted artillery which is formed of two sprocket gear-wheels B B, properly fastened to the front wheels X X, preferably by means of clasps and nuts M M, as shown in the drawings, and a shaft D D with smaller sprocket gear-wheels C C, properly fastened to each end, and two pulleys A A, provided with metal ends with proper notches L L, properly fastened to the shaft D D, as shown in the drawings, and braces E E E E, provided with boxing at one end for the shaft D D to turn in, properly fastened to the axletree, and two dogs H H, fastened to the axletree O to properly fit the notches L L in pulleys A A,

and a spring K, fastened to the tongue Z with one end under the axletree O, and two adjustable sprocket-chains Y Y to adjust to sprocket gear-wheels B B and C C, and two ropes S S, provided with hooks G G, substantially as shown in the drawings.

In using my improved moving device the sprocket-chain is put onto the sprocket gear-wheels, the hook on one of the ropes is hooked to the whiffletree, the dogs are put into the notches to prevent the load from going back when the team stops, the team is driven ahead, the rope turns the pulleys and the shaft, the smaller sprocket-wheels turn the wagon-wheels, and the load is moved comfortably and easily.

By my improved construction a very strong power is provided which is at the same time light and durable and can be cheaply made and will be found very convenient and effective for drawing heavy loads out of ruts, mud-holes, and bad roads and up hills.

I might employ cog-gearing or might fasten the gearing to the hind wheels, but it is not my preferred construction.

Two pulleys and two ropes are provided which can be used singly or both at a time. The spring K is for the purpose of holding the tongue up from the ground when using the power.

What I claim, and desire to secure by Letters Patent, is—

1. In a device for the purpose described, the combination with a truck having suitable wheels, of a shaft mounted thereon, a drum on said shaft, a rope secured to said drum provided with a draft device, and a drive connection from said shaft to one of said truck-wheels, substantially as set forth.

2. In a device for the purpose specified, the combination with a truck having suitable wheels, of a shaft mounted on said truck, a drum on said shaft, a rope secured to said drum and provided with means for detachably connecting a draft device, a ratchet and pawl to prevent the return movement of said shaft, and a driving connection from said shaft to one of said wheels, substantially as set forth.

3. In a device for the purpose specified, the combination with a truck having suitable wheels, of a shaft mounted on said truck, a

drum on said shaft, a rope secured to said drum and provided with means for detachably connecting a draft device, a ratchet and pawl to prevent the return movement of said shaft, a driving connection from said shaft to one of said wheels, and means for supporting the tongue during the operating of the device, substantially as described.

4. In a device of the character described, the combination with an axle, tongue, and wheels, of a shaft journaled in bearings car-

ried by said axle and tongue, a drum on said shaft, a rope secured to said drum, a draft device for said rope, means to prevent the return movement of said shaft, and a drive connection from said shaft to one of said wheels, substantially as described. 15
